UNITED STATES PATENT OFFICE.

J. P. GILLESPIE, OF NEW ALBANY, INDIANA.

IMPROVEMENT IN METALLIC CARTRIDGES.

Specification forming part of Letters Patent No. **33,481**, dated October 15, 1861.

To all whom it may concern:

Be it known that I, J. P. GILLESPIE, of New Albany, in the county of Floyd and State of Indiana, have invented certain new and useful Improvements in Metallic Cartridges; and I do hereby declare that the following is a full, clear, and exact description of the same, reference being had to the accompanying drawings, and to the letters of reference marked thereon.

In the annexed drawings, making part of this specification, A represents the metallic cartridge-case, which is constructed as represented in the figures, having at its rear end a flange, B; also, in a recess in the rear end, a nipple, C, which communicates with the interior of the case. Within the mouth of the case are provided small points or pins, *xxxx*, which serve to form a screw-thread upon the ball when it is inserted in the case, and thus hold it firmly and securely in its proper position. D represents the ball, which is constructed as represented, and screwed into the mouth of

the case. The metal at the rear of the case may be cut off on the line *zz*, if desired, leaving the nipple exposed. The case A may be made a little larger at the rear than at the front, so as to allow it to draw out readily. This cartridge is to be used with breech-loading cannon, as well as small-arms.

Having thus fully described my invention, what I claim is—

The within-described cartridge-case, provided with points or pins *xx* near its mouth, for forming a thread upon the ball and retaining it in its position, substantially as herein set forth.

In witness that I claim the foregoing I have hereunto set my hand in the presence of the subscribing witnesses.

J. P. GILLESPIE.

Witnesses:

JARED C. JOCELYN,
DAVID WILKINSON.
